US00D763565S

(12) **United States Design Patent**
Casperson(10) **Patent No.:** **US D763,565 S**
(45) **Date of Patent:** **** Aug. 16, 2016**(54) **ELASTOMERIC TUBULAR DRAWSTRING
CASING**701,305 A * 6/1902 Daughtry et al. A47J 45/10
16/435(71) Applicant: **Regina B. Casperson**, Jenkins, MN
(US)713,149 A 11/1902 Quarmbby
753,499 A 3/1904 Klarle
767,891 A 8/1904 Isakson
785,561 A 3/1905 Latimer
819,884 A 5/1906 Higgins
839,346 A 12/1906 Wardman(72) Inventor: **Regina B. Casperson**, Jenkins, MN
(US)

(Continued)

(***) Term: **14 Years**

Primary Examiner — John Windmuller

(21) Appl. No.: **29/526,460**

Assistant Examiner — Steven Czyz

(22) Filed: **May 8, 2015**

(74) Attorney, Agent, or Firm — Albert W. Watkins

(51) **LOC (10) Cl.** .... 03-99**CLAIM**(52) **U.S. Cl.**I claim the ornamental design for an elastomeric tubular
drawstring casing, as shown and described.(53) **USPC** .... D3/18**DESCRIPTION**(58) **Field of Classification Search**FIG. 1 is a perspective view showing my new design;
FIG. 2 is a front view thereof, with the back view, bottom
view, and top view being identical thereto;
FIG. 3 is a right side view, with the left side view being
identical thereto;

USPC D3/12, 18; D2/978; D8/303; D12/114;

FIG. 4 is a front view thereof;

D23/266

FIG. 5 is a front view showing my new design in a partially
rolled configuration, with the back view, bottom view, and top
view being identical thereto;

CPC .. B65D 81/3886; F16L 37/002; F16L 25/023;

FIG. 6 is a left side view showing my new design in a partially
rolled configuration;

F16L 21/005; E03B 7/10; A22C 13/0013

FIG. 7 is a right side view showing my new design in a
partially rolled configuration;

See application file for complete search history.

FIG. 8 is a perspective view showing a second embodiment of
my new design;(56) **References Cited**FIG. 9 is a front view of the second embodiment, with the
back view, bottom view, and top view being identical thereto;**U.S. PATENT DOCUMENTS**

and,

FIG. 10 is a right side view of the second embodiment, with
the left side view being identical thereto.The drawstring depicted by broken lines in FIG. 4 has been
shown for the purpose of illustrating environment that forms
no part of the claimed design.**1 Claim, 2 Drawing Sheets**US D763,565 S
